UNITED STATES PATENT OFFICE.

THOMAS J. TOBIN, OF ALBANY, NEW YORK, ASSIGNOR TO THE BRYANT ELECTRIC COMPANY, OF BRIDGEPORT, CONNECTICUT, A CORPORATION OF CONNECTICUT.

ELECTRIC SAFETY DEVICE.

1,159,294.

Specification of Letters Patent.

Patented Nov. 2, 1915.

Application filed July 3, 1913. Serial No. 777,352.

To all whom it may concern:

Be it known that I, THOMAS J. TOBIN, a citizen of the United States of America, and residing at Albany, in the county of Albany 5 and State of New York, have invented a certain new and Improved Electric Safety Device, of which the following is a specification.

My invention relates to electric safety devices and receptacles therefor, the object of my invention being to provide an improved plug and receptacle of the type designed to render it impossible to overfuse a circuit.

In the accompanying drawing, Figure 1 is a vertical section through a fuse plug and receptacle, detached, in which my invention is illustratively embodied. Fig. 2 is a similar view showing a plug and receptacle designed for a circuit of smaller capacity; 20 Figs. 3 and 4 are inverted plan views of the plugs shown in Figs. 1 and 2 respectively; and Fig. 5 is a broken section through a plug of modified construction.

Various devices have been suggested by 25 which to prevent the adjustment of a fuse plug of too great capacity in a receptacle arranged in a circuit of relatively low capacity. So far as I am aware these devices have been of a type which permit the adjustment of the plug in the receptacle, but prevent the engagement of certain of the operating contacts unless the plug is of proper capacity. One prominent disadvantage of this type of plug resides in the fact 30 that it is impossible to tell whether or not the circuit has been completed through the plug without making a test of some character in the circuit beyond the plug and this is often not convenient. I am also aware 35 that it has been proposed to provide an elongated center contact rod below the body of the fuse plug, which enters a well of predetermined diameter below the ordinary bottom level of the receptacle. Such a construction is extremely inconvenient since it necessitates both fuse plug and receptacle being made almost twice normal length, if the objects which I attain are to be accomplished. The present invention avoids this 40 difficulty by providing a guard which prevents even the partial insertion of the plug, unless the fuse is of proper capacity for the circuit. As here shown, the fuse plug comprises the usual insulating body 10 on which

is mounted the screw shell 11. Within the 55 plug body is arranged the fuse 12 which is soldered at 13 to the center contact. The latter comprises a perforated guard washer 14 arranged at the lower extremity of the plug and provided with wings 15 which extend upward therefrom into the interior of the plug. They are preferably of spring metal, in order to insure a close contact with the center contact of the receptacle. The latter comprises the usual shell contact 16 60 mounted on the porcelain base 17 and in contact with the wire terminal 18. The center contact comprises a pin 19, preferably threaded at its lower end into the strap 20 which is connected to the other wire terminal 21. A washer 22 lying beneath a shoulder 23 on the pin 19 overlies the centrally apertured base of the shell 16 from which it is electrically insulated by the washer 24. The pin 19 is of such diameter with relation 65 to the guard washer 14 that while it passes therethrough, the fit is quite snug.

In Fig. 2 is shown a plug designed to carry less current. In this case the construction is in all main features the same as 80 in that just described, with the single exception of the diameter of the pin 19^a and of the perforation in the guard washer 14^a. Both are made larger than in the construction shown in Fig. 1. As a result of this 85 variation in size, which is in each case arbitrarily predetermined with relation to the capacity of the plug, it is obviously impossible to adjust in the receptacle of Fig. 2, the plug of Fig. 1, since the aperture in the 90 guard washer 14 of Fig. 1 is too small to pass over the pin 19^a which is of larger diameter. While, on the other hand, the fuse plug of Fig. 2 may be adjusted in the receptacle of Fig. 1 by reason of the fact 95 that its guard washer 14^a has a perforation of a diameter greater than that of the pin 19, yet this is attended by no danger, since the fuse in the plug of Fig. 2 is of less capacity than the circuit in which the receptacle of Fig. 1 is arranged, can safely stand.

As a possible modification the construction shown in Fig. 5 may be employed. Here the guard washer is substituted by a hollow rivet 25, the diameter of which is 100 predetermined with relation to the capacity of the fuse in like manner as in the previous constructions. Spring contacts 26 are se-

cured within the plug body by the rivet which is, however, insulated therefrom by the washer 29. Thus in this construction there can be no possible completion of the circuit through the plug until the pin has entered the interior of the latter. This is an added feature of safety which prevents possible misuse of the plug. Various other modifications of the construction will readily suggest themselves, such for instance as making the pins and apertures in the guard washers of different shapes for circuits of different capacities.

I claim as my invention:—

1. A hollow fuse plug having a fuse within the same, a perforated guard at the entering end of the plug, the diameter of the perforation having a predetermined relation to the capacity of the fuse within the plug, together with spring contact means within the plug projecting over the area of the hole in the guard to engage an entering contact member, for the purpose described.

2. A plug receptacle having an insulating base, a screw shell supported thereon, a conducting strap let into the lower face of said base, a center contact pin engaging said strap and projecting into the interior of said screw shell, said pin having a cross section predetermined with relation to the capacity of the circuit in which the receptacle is arranged.

3. A fuse plug receptacle comprising an insulating base having a screw shell side contact supported thereon and a center contact pin mounted on said base in axial position with relation to said shell and projecting upwardly within the latter to substantially the height of said screw shell, said pin having a diameter predetermined with relation to the capacity of the receptacle circuit and serving as a guard, in combination with a fuse plug having an axial aperture at its entering end to receive said center contact guard pin, said aperture being predeter-

mined with relation to the capacity of the plug, for the purpose described.

4. A fuse plug receptacle comprising an insulating base having a screw shell supported thereon and a center contact pin having a diameter predetermined with relation to the capacity of the receptacle circuit and projecting upward substantially the height of the screw shell, in combination with a fuse plug hollowed to afford a contact chamber and a center contact apertured to permit the entry of said contact pin into the contact chamber, the diameter of the aperture of said center contact being predetermined with relation to the capacity of the circuit which the plug is designed to protect.

5. A fuse plug receptacle comprising an insulating base having wire terminals on its upper face, screw shell and center contact respectively connected to said wire terminals, the center contact comprising a pin having a diameter predetermined with relation to the capacity of the receptacle circuit, in combination with a fuse plug having a center contact adapted to engage said pin and a guard disk at the entering end of said plug, said guard disk having an aperture the diameter of which is predetermined with relation to the capacity of the plug fuse and through which said center contact pin passes in the inserted position of the plug, said guard pin projecting outward from the bottom of the receptacle screw shell a distance sufficient to prevent engagement between said screw shell and the cooperating member of the plug until the pin has passed through the guard disk.

In testimony whereof I have signed my name to this specification, in the presence of two subscribing witnesses.

THOMAS J. TOBIN.
